UNITED STATES PATENT OFFICE.

ARTHUR W. ARNOLD, OF PORTLAND, OREGON, ASSIGNOR TO SAFETY AND ECONOMY DAMPER COMPANY, OF PORTLAND, OREGON, A CORPORATION OF OREGON.

AUTOMATIC DAMPER.

970,598.

Specification of Letters Patent. Patented Sept. 20, 1910.

Application filed September 8, 1908. Serial No. 452,063.

To all whom it may concern:

Be it known that I, ARTHUR W. ARNOLD, a citizen of the United States, residing at Portland, county of Multnomah, and State of Oregon, (whose address is 423 Sherlock Building,) have invented a new and useful Automatic Damper, of which the following is a specification.

It is a well known physical law that heated gases or vapors rise, or have tendency to rise, the velocity with which they rise being directly proportional to the degree of heat contained therein. This is especially true in flues, pipes, or chimneys leading from heated furnaces and great difficulty has been experienced in regulating the degree of heat generated in such furnaces because the hotter they become, the greater is the tendency for the gases to escape and, therefore, the greater the suction or draft produced in such flues, pipes, or chimneys leading therefrom and, therefore, the greater the combustion. To utilize the force of the rise of these gases in regulating such draft is one purpose of this invention, because the force generated varies in accordance with the velocity. Under varying conditions more or less force is generated within the flue, due to the upward passage of the heated fluids and, therefore, a damper to meet these varying conditions should be so made that it may be readily adjusted and yet be simple of construction. I attain these objects by the mechanisms illustrated in the accompanying drawings, in which—

Figure 1 is the side elevation of the pipe or flue, parts being broken away to show the damper in place. The full lines in Fig. 1 show the damper in normal inoperative position while the dotted lines show the two blades partially extended, thus lessening the effective area of the flue for the passage of the gases and, therefore, the draft upon the furnace. Fig. 2 is a vertical sectional view of the flue taken at right angles to the view of Fig. 1, and showing the damper and operating devices in side elevation. Fig. 3 is a plan view of the device with the parts in the position shown in full lines in Fig. 1. Fig. 4 is a plan of the blank from which the damper blade is made and the arm with which it is operated.

Similar reference characters refer to similar parts throughout the several views.

1 is a joint of the flue above the place of 55 the insertion of the damper.

2 is the joint below while 3 is a sleeve into which the damper is placed, passing through it on opposite sides.

It will be understood that the flue joints 60 and sleeve 3 will be of any suitable construction and cross sectional form, but this invention is designed especially for application to ordinary domestic stove pipes.

The damper mechanism below described, 65 will preferably be assembled in place in the sleeve 3 at the factory, and thus placed on the market as a complete article of manufacture, ready to be inserted between any two stove pipe joints, as indicated, by any person whether skilled or unskilled. 70

It is to be understood that while a sleeve is shown as bearing the other portions of the damper the sleeve as a separate element is not absolutely required, since the damper 75 blades and the coöperating parts may be fitted to an ordinary stove pipe or flue, especially when the devices are being made in connection with the flue pipes at the factory. It is to be understood in this connection that applicant does not desire to be limited to a construction in which a sleeve as a separate element is employed. 80

Parts 1 and 2 do not touch each other; the space between them being somewhat greater 85 than the rolled part which forms the support or axis of the damper blade.

4 is one damper blade which in form substantially conforms to the form of the inner wall of the flue. 5 is the other damper 90 blade. The two, when extended into a horizontal plane, completely stop the passage of the gases. To operate blade 4 there is an arm 6 and to operate blade 5 there is an arm 7, both of which are parts of blades 4 and 5. 95

8 are small circular holes in arms 6 and 7 which are for the purpose of allowing connecting links 9 and 10 to be engaged therein.

11 is a counter weight. As the conditions vary, due to a strong wind or change in atmospheric conditions, more or less weight is required to operate the damper successfully. This is attained by variably inserting the connecting links which support the counter weight in these various openings. 100

When the damper blade has been formed from the blank into the finished blade there will be formed bearings 16 and 17 for en- 105

gagement with the sleeve, and at any suitable points there may be provided thrust lugs to prevent endwise movement of the same, such being shown herein as comprising a lug 13 to engage the inner wall of the flue and a coöperating lug 12 to engage the outer wall of the sleeve, thus holding the blade in position in the sleeve when once it is placed therein and made secure, as indicated. To keep them from passing through more than ninety degrees, two arms 14 and 15 come in contact with each other. The damper blades being stamped from sheet metal, the stop arms 14 and 15 are flexible, whereby they may be readily bent toward and from each other to vary the degree of angular movement which they will permit the blades to make, according to various requirements.

20 I claim:

1. In an automatic damper, a pair of damper blades, operating levers connected to said blades and extending above the axes thereof in directions opposite from the directions in which the blades extend, and a counterweight connected to both of said levers to govern the rotation of the blades on their axes.
2. In an automatic damper, a plurality of damper blades, operating levers connected to said blades and extending from the axes thereof in directions opposite from the directions in which the blades extend, and adjustable stop arms to variably limit the extent of angular movement of the blades.
3. In an automatic damper, the combination of a sleeve, a pair of damper blades

journaled for rotation therein on parallel axes, a lever connected to each blade and projecting above its axis, a stop arm likewise connected to each blade, each blade and its lever and stop arm being formed from a single blank, and a weight adjustably connected to both of said levers to counterbalance the effective weight of the blades throughout their movements.

4. In an automatic damper, the combination of a sleeve, damper blades journaled therein, operating levers connected to said blades and extending above the axes thereof in directions opposite from the directions in which the blades extend, thrust means connected to the blades to prevent movement thereof endwise of their axes, links connected pivotally to said levers, and a weight suspended from both of the links.

5. In an automatic damper, a pair of damper blades, operating levers connected to said blades and extending therefrom in opposite directions, and counterbalancing means connected to said levers, such counterbalancing means being capable of adjustment to permit free movement of said blades upon a slight variation in the force of the draft passing through the sleeve.

In testimony that I claim the foregoing as my own, I have hereto affixed my signature in the presence of two witnesses this 1 day of Sept. 1908.

ARTHUR W. ARNOLD.
